Primary Examiner—Ted Shooman*Assistant Examiner*—C. Tuttle*Attorney, Agent, or Firm*—Thomas, Kayden, Horstemeyer & Risley**[57] CLAIM**

The ornamental design for a fingernail clipper with finger support loop, as shown and described.

DESCRIPTION

FIG. 1 is a perspective illustration of the fingernail clipper with finger support loop;

FIG. 2 is a side elevational view thereof, with the opposite side being a mirror image;

FIG. 3 is a front view thereof;

FIG. 4 is a rear view thereof;

FIG. 5 is a top view thereof; and,

FIG. 6 is a bottom view thereof.

The portions of the clipper that are neither shown nor described herein are not being claimed.
